UNITED STATES PATENT OFFICE

AXEL M. WALSTROM, OF MINNEAPOLIS, MINNESOTA, ASSIGNOR TO ELGIN BUTTER TUB COMPANY, OF ELGIN, ILLINOIS, A CORPORATION OF ILLINOIS

FASTENER FOR CONTAINER COVERS

Application filed April 14, 1927. Serial No. 183,692.

This invention relates to a container and particularly to a device adapted to hold a cover on a container. While the device is capable of application to containers of various kinds and shapes, it particularly is designed, and in the embodiment of the invention illustrated, is shown as applied to a cylindrical container. Such containers which are often of slightly tapered form, are now commonly used as tubs for containing butter, lard and other similar materials.

It is desirable, in such a container, to have some means which will positively hold the cover in place on the container or tub, and it is further desirable to have such means which will not protrude so as to catch on the hands of the persons handling the tub or on other objects. It is also desirable to have a fastening means which will prevent any rotative movement of the cover and which will be easily applied and simple and inexpensive to make.

It is an object of this invention, therefore, to provide a very simple and efficient means for holding a cover on a container such as a butter tub.

It is another object of the invention to provide a simple and efficient holding means for a container cover having diverging members adapted to be engaged in the material of the tub.

It is still another object of the invention to provide a simple and efficient holding means for a tub adapted to be made from a simple rod bent into U-shape and having its bight portion further bent into a hook or U-shaped portion, adapted to engage with the cover.

It is also an object of this invention to provide a novel method of making a fastener for a container.

These and other objects and advantages of the invention will be fully set forth in the following description made in connection with the accompanying drawings, in which like reference characters refer to similar parts throughout the several views and in which:—

Fig. 1 is a view in side elevation of the top

portion of the container with the cover and holding means;

Fig. 2 is a vertical radial section through one side of the container and cover;

Fig. 3 is a view in side elevation of the holding means in uncompleted form;

Fig. 4 is a view in side elevation of the device shown in Fig. 3;

Fig. 5 is a perspective view of a modified form of the holder;

Referring to the drawings, a cylindrical container such as a butter tub is shown at 10 having thereon the cover 11. While this cover may be of various forms having a flange depending at the side of the tub, in the embodiment of the invention illustrated the particular cover shown has a central portion 11a with a rim or flange portion 11b, the cover being beveled at its edge as shown at 11c and flange 11b being rolled about and thus secured to said beveled portion 11c as shown at 11d. The flange 11b as shown has a bead 11e at its lower edge with its concave side directed inwardly. The cover 11 is provided at circumferentially spaced points just above the bead 11e with somewhat elongated slots 11f extending circumferentially of the rim.

The fastener forming the subject matter of the present invention is formed from a length of simple round rod. The portion 15a of the fastener is bent substantially midway of its length about an axis extending parallel to its flat side so that it is of U-shaped form shown at 15c in Fig. 1. The round portions 15d of the fastener are then bent into diverging form as shown in Fig. 1, and the fastener is then in condition to be applied to the container.

In applying the fastener to the tub, the portion 15c is hooked through the slots 11f. The portions 15b are then driven into the material of the tub as shown in Figs. 1 and 2, the cover being pulled down tight on the top of the container before the portions 15b are driven in. When the fastener is then in place on the tub, the lid will be held securely in place. The free end of the hook on member 15c is, as shown in Fig. 2, next to the tub. There is thus no possibility of the hook straightening and in fact, the material of the

fastener is too stiff for any such straightening movement. It will be seen that there are no projections on the fastener which might catch on the hands or other objects, and there are no fasteners which might become loose and protrude to form such projections. The diverging legs 15d of the fastener give a trussed effect so that the fastener is quite rigid against lateral or circumferential movement. The cover 11 is thus held firmly against any rotative movement on the tub.

In the modification shown in Fig. 6, a strip of material 16 is shown, which may also be used to form a fastener for the cover 11. The strip 16 is reversely bent at one end as shown at 16a in Fig. 5. Two or more fasteners 17 are driven through the other end of the strip. When the strip is applied to the container, the hook portion 16a will be passed through one of the slots 11f, the cover drawn down tightly and the nails or fasteners 17 will be driven into the tub. The cover will thus be held tightly in place.

From the above description it is seen that applicant has provided a very simple and efficient holding means for a container cover and the holding means is made from simple material and can be easily and inexpensively produced. The said holding means is easily applied and very efficient in operation, holding the cover tightly in place on the container and acting to prevent any rotative movement thereof. The device has been amply demonstrated in actual practice and found to be very successful and efficient.

It will, of course, be understood that various changes may be made in the form, details, arrangement and proportions of the device and in the steps and sequence of steps of the method, without departing from the scope of applicant's invention, which, generally stated, consists in a method and device capable of carrying out the objects above set forth, such as disclosed and defined in the appended claims.

What is claimed is:—

1. A fastening means for the cover of a container comprising a rod bent substantially at its central portion and having its bight portion flattened for a considerable distance so as to be bent reversely to form a hook adapted to engage through a slot adjacent the edge of said cover, the unflattened portions of said rod extending from said flattened portion in diverging relation and having their end portions bent substantially at right angles and sharpened so as to enter the material of said container.

2. A fastening means for the cover of a container, which cover has a depending rim at the side thereof having a slot therethrough comprising a rod bent substantially at its central portion to have closely adjacent parallel sides connected by a bight portion, said device being bent some distance from said

bight portion at right angles to said first mentioned bend to form a hook having its sides in close proximity, said hook extending through said slot and engaging the same with its curved end, the free ends of said rod diverging and having inwardly bent sharpened ends adapted to be driven into the side of said container.

3. A fastener for container covers comprising a hook adapted to be extended through a portion of a cover, said hook having lower laterally diverging portions having ends adapted to be embedded in the side of the container below the cover to secure the cover in place, stabilize the same and prevent sliding movement thereof relative to the container.

4. A fastener for container covers having a looped upper end forming a hook adapted to be inserted through a slot in the edge of a container cover, said fastener having lower portions joining the outer side of said looped upper end and extending downwardly in laterally diverging relation and terminating in inwardly bent pointed ends adapted to be driven into the side of the container below the cover and one at either side of said looped upper end.

5. In combination, a tub provided with a cover having a rim projecting downwardly over the upper portions of the side of the tub and provided with a bead having spaced slots cut therethrough, and a plurality of fasteners, each fastener having a hook portion at its upper end bent inwardly and downwardly through one of said slots in said rim and bearing against the side of the container, said fastener having a lower end joining the outer portion of the upper end of the fastener and overlapping said hook portion, the lower end of the fastener being secured to the side of the tub below said rim.

In testimony whereof I affix my signature.
AXEL M. WALSTROM.
